Primary Examiner — Ricky Pham(74) *Attorney, Agent, or Firm* — Adler Pollock & Sheehan P.C.; Daniel J. Holmander, Esq.; George N. Chaclas, Esq.(57) **CLAIM**

The ornamental design for a pan, as shown and described.

DESCRIPTION

FIG. 1 is a perspective view of one embodiment of the pan; FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a right side view of the pan of FIG. 1 positioned over a gas stove burner, which is shown in broken lines; and, FIG. 9 is perspective of a second embodiment of the pan of FIG. 1 indicating surface shading for metal.

The elements depicted in broken lines in the various figures are included for environmental purposes only, and form no part of the claimed design.
